UNITED STATES PATENT OFFICE.

JOHN E. MCWORTER, OF ST. LOUIS, MISSOURI.

AEROPLANE.

1,115,710.

Specification of Letters Patent.

Patented Nov. 3, 1914.

Application filed June 26, 1911. Serial No. 635,440.

To all whom it may concern:

Be it known that I, JOHN E. MCWORTER, a citizen of the United States, residing at St. Louis, Missouri, have invented a certain new and useful Improvement in Aeroplanes, of which the following is a full, clear, and exact description, such as will enable others skilled in the art to which it appertains to make and use the same.

10 This invention relates to aeroplanes.

One object of the invention is to provide an aeroplane having combined propelling and sustaining planes which are so arranged that they give a constant lift and any increase in the speed of the machine through the air causes a greater volume of air to be brought into contact with the planes and thus, by reason of the greater resistance offered by the air, the rotary movement of the 20 blades is retarded, thereby producing an aeroplane in which the efficiency of the propellers increases as the speed of flight increases for the amount of power required to drive the propellers decreases as their 25 relative velocity decreases.

Another object of the invention is to provide an aeroplane which is so constructed that it can rise directly from the ground through the action of propellers with a vertical lift, thereby producing an aeroplane less subject to the ordinary variations or changes in the velocity of the wind and one not wholly dependent upon the velocity with 30 which its lifting and supporting planes cut through the air in the direction of flight.

Another object is to provide an aeroplane of novel construction in which the means that propels the machine through the air also acts to sustain the machine in the air.

40 Another object is to provide an aeroplane of the character described in which the combined propelling and sustaining planes are so constructed and arranged that they offer very little resistance to the forward flight of 45 the machine.

Another object is to provide an aeroplane having propeller planes or blades which are so designed, arranged and operated that a machine of practical size can be equipped 50 with a relatively great area of propeller blade surface, thereby greatly increasing the propeller thrust per applied horse-power above that obtained from the ordinary screw form of propeller under working conditions.

55 Another object is to provide an aeroplane

in which the means that sustains the machine in the air is located above the center of gravity of the machine, thereby enabling the equilibrium of the machine to be maintained easily.

Another object is to provide a combined propelling and sustaining device for aeroplanes that is light and strong and in which the area of the propelling planes is as great as that of the sustaining planes of the aeroplanes now in general use. And still another object is to provide a light and strong aeroplane which is so constructed that the strains are equalized and distributed uniformly to all parts of the body of the machine and to the propelling and sustaining devices when the machine is in operation, thereby permitting said elements to be formed from comparatively small, light-weight members.

Other objects and desirable features of my invention will be hereinafter pointed out.

Figure 1 of the drawings is a perspective view of an aeroplane constructed in accordance with my invention; Fig. 2 is a top plan view of the body or framework of the machine which supports the operator and the motor used for actuating the propellers; Fig. 3 is a side elevational view of the body of the machine; and Fig. 4 is a sectional view of the gears and sprocket wheels on the shaft of the motor which coöperates with the driving members that actuate the propellers.

Briefly described, my improved aeroplane consists of a body or frame of any preferred design which carries the operator, the motor, and the devices for controlling and guiding the machine, one or more pairs of combined propelling and sustaining devices, each of which comprises a plurality of planes, wings or blades which are so disposed that the resistance which the air offers to the rotary movement of same is in a vertical direction, means for rotating said propelling and sustaining devices in opposite directions, and means for causing the planes or wings of same to feather or turn from a horizontal position into a vertical position when they reach such a point in the cycle of operations of the devices that the air will exert downward pressure on same instead of a lifting or upward pressure. The machine herein shown, which represents the pre-

ferred form of my invention is provided with only one pair of combined propelling and sustaining devices but I wish it to be understood that it is immaterial so far as my broad idea is concerned whether the machine is provided with two or more pairs of such devices.

Referring to the drawings which illustrate the preferred form of my invention, A 13 designates the body or supporting frame of the machine which carries the motor and the operator, and B designates a pair of combined propelling and sustaining devices arranged above the frame A and on opposite 15 sides of same, as shown in Fig. 1. The frame A may be constructed in various ways but I prefer to build it from lightweight bars or rods 1 and stay-wires 2 which are so combined and arranged that a lightweight trussed 20 skeleton structure is produced which has sufficient strength to carry the operator, the motor, and the various other elements used to control the machine. The body A of the machine herein shown is substantially box-shaped and is provided at its front end 25 with forwardly projecting members 3 which converge at a common point and thus form a pyramidal-shaped extension on the front of the body A. The propelling and 30 sustaining devices B are supported by suitable braces 4 which are connected to the body A of the machine, the number and the particular arrangement of said braces being immaterial so far as my invention is concerned, although I prefer to connect the 35 braces 4 at the front of the machine to the pyramidal-shaped projection 3 on the body A of the machine, and also connect the upper ends of said braces together by means of 40 horizontally disposed cross braces 4^a, as shown in Fig. 1, so as to produce a strong and rigid supporting structure for the propelling and sustaining devices B.

Each of the combined propelling and sustaining devices B consists of a horizontally disposed axle provided with radially projecting supports in which planes or wings 45 are pivotally mounted, each of the devices B of the machine herein shown having four 50 planes or wings w, x, y, z, whose longitudinal axes extend parallel to the center axle of the device. As both of the devices B are of the same construction I will only refer to one of them in specifically describing the 55 construction of the combined propelling and sustaining devices of the machine. Instead of using a solid shaft to form the axle of the device B, I prefer to use a light box-shaped skeleton structure composed of longitudinally extending bars or rods 5, cross rods 6, and truss-wires 7 arranged a sufficient 60 distance from the center of rotation to safely withstand a torsional strain which if carried by a solid central axle would be very 65 great. Said axle is provided with hubs 8

that are carried by X-shaped braces 9 secured to the ends of the axle, and the ends of said X-shaped braces project radially from the axle so as to form suitable supports for the planes or wings w, x, y, z, of the device. Short stub shafts may be used for supporting the ends of the device B but I prefer to use a single shaft 10 which extends longitudinally of the axle of said device B through both of the hubs 8 thereon, the ends of the shaft 10 being supported in suitable bearings 11 connected to the braces 4 and 4^a that are fastened to the body A of the machine. Each of the planes or wing blades w, x, y, z, consists of a rectangular-shaped frame composed of one or more bars or rods arranged on either side of and parallel to a center shaft, and a plurality of cross-bars or rods attached to the center shaft and to the bars or rods on either side 80 of same, and truss-wires 12 which lead from the corners, side, ends and other suitable points of the frame to a center strut 13, as shown in Fig. 1, wherein it will be seen that a set of truss-wires are provided for each side of the plane so as to hold the plane rigid and to resist and carry the strains to which the plane is subjected when either side is moving against the air. Each blade presents one face against the air during one 90 revolution of the propeller and the other face during the next revolution, etc.

The combined propelling and sustaining devices B are rotated in opposite directions, preferably outwardly away from the body A 100 of the machine, as indicated by the arrows in Fig. 1. Any suitable means may be used for this purpose such, for example, as a motor C on the body A of the machine and driving members 14 which transmit rotary movement from the shaft of the motor to the devices B. The driving members 14 of the machine herein shown consist of sprocket chains 14 which pass over sprocket wheels 15 on the shaft 16 of the motor C and over 110 sprocket teeth on relatively large rims 17 that are connected to the members which form the hollow trussed axles of the combined propelling and sustaining devices B, the sprocket chain which co-operates with 115 the device B at the left-hand side of the machine being crossed so that said device will rotate in an opposite direction to the device B at the right hand side of the machine.

In order that the equilibrium of the machine will be maintained automatically I have provided the machine with means which causes the rotative velocity of the combined propelling and sustaining device B on one side of the machine to be accelerated automatically when the rotative velocity of the device B on the other side of the machine is retarded, thus compensating for variations in the wind currents on opposite sides of the machine. The means that I pre- 120 125 130

fer to use for accomplishing this consists of a balancing gearing combined with the mechanism which drives the combined propelling and sustaining devices B. Any suitable type of differential gearing may be used, and in the embodiment of my invention herein shown a differential gearing 18 is combined with the sprocket wheels 15, as shown in Fig. 4 of the drawings. Said gearing 10 consists of a member securely fastened to the shaft 16 and provided with a plurality of rotatably mounted beveled pinions 18 that mesh with beveled gears on the sprocket wheels 15, the member which carries the pinions 18 being arranged between said sprocket wheels. The sprocket wheels 15 are loosely mounted on the shaft 16 so that the member which carries the pinions 18 transmits movement from the shaft 16 to the sprocket wheels 15. Such a construction gives an equal pull to the two sprocket chains 14 and also permits the combined propelling and sustaining device B on one side of the machine to rotate at a different speed from the device B on the other side of the machine, thus making the lift of one device B equal to the lift of the other device B when the device B on one side of the machine encounters air currents moving at a different speed or in a different direction from those encountered at the same time by the device B on the other side of the machine. Such a construction also causes the rotative velocity of one of the devices B to be retarded and that of the other device B to be accelerated automatically to such an extent that their lift will remain equal. Consequently, the center of lift of the devices B will be maintained at a point midway between the axles of said devices and at some distance above the center of weight to the machine, thus causing the lateral equilibrium of the machine to be maintained automatically.

By referring to Fig. 1 it will be seen that the rims 17 on the devices B are of sufficient diameter with relation to the sprocket wheels 15 on the shaft of the motor to cause the devices B to rotate slowly. The rims 17 are preferably connected to the outer ends of the X-shaped braces 9 at the front ends of the axles of the devices B and are connected to the hubs 8 coöperating with said X-shaped braces by means of spokes 19; and similar rims 17^a which, however, are not provided with sprocket teeth, are connected to the X-shaped braces at the rear ends of the axles of the devices B so as to reinforce and strengthen the members in which the planes or wings w, x, y and z are mounted. It will, of course, be understood that power could be applied to the axles of the combined propelling and sustaining devices B in various other ways, but I prefer the construction herein shown on account of its simplicity and efficiency, the power being applied to the

devices B at a point adjacent the pivots or longitudinal axes of the planes or wings on said devices.

The means which I prefer to use for causing the planes or wings w, x, y, z, to feather or turn from a horizontal position into a vertical position and then back to a horizontal position during each cycle of operations of the devices B consists of driving members such, for example, as sprocket chains 20 which pass over sprocket wheels 21 secured to the rear ends of the planes or wings and also over sprocket wheels 22 rigidly connected to the horizontally disposed shafts 10 on which the devices B are rotatably mounted. The shaft 10 of each device B is provided with four sprocket wheels 22, as shown in Figs. 1 and 2, and a separate driving member or chain 20 is employed for each wing or plane. In view of the fact that the shafts 10 and the sprocket wheels 22 thereon remain at rest while the devices B are rotating, each of the planes w, x, y, z, will make a half revolution during one complete revolution of the device B on which they are mounted, the sprocket wheels 21 having twice as many teeth as the sprocket wheels 22. When the wings or planes y reach the position shown in Fig. 1 they will offer practically no resistance to the air in a vertical direction because they lie in vertical planes, but as the devices B continue to rotate the planes y move gradually from a vertical position into a horizontal position, as indicated by the wings w in Fig. 1 at which point they offer the maximum resistance in a vertical direction to the air. When the wings move downwardly and upwardly from a horizontal position into a vertical position the efficiency of same gradually decreases but while the wings are moving from a neutral or vertical position, as indicated by the wings y in Fig. 1, into a horizontal position, as indicated by the wings w, the efficiency of same gradually increases. In other words, each wing of each of the devices B reaches a neutral position in the cycle of operations of the devices B, at which point it offers no vertical resistance to the air, but in traveling from this neutral position into a horizontal position the resistance which it offers to the air in a vertical direction is gradually increased until the maximum position is reached, and after it has passed this maximum position and is moving back to the neutral position the resistance which it offers to the air in a vertical direction is gradually decreased. The wings y offer resistance to the air in a lateral or horizontal direction and thus tend to prevent the machine from skidding or moving sidewise out of the course in which it is traveling. I have herein referred to the wing w as occupying a horizontal position when the wing y occupies a vertical position, but it will, of

course, be understood that when the devices B rotate in the direction indicated by the arrows in Fig. 1, each wing on same will assume a horizontal position and a vertical position once during each complete revolution of the devices B.

In order that the operator may vary the maximum working point of the wings so as to control the ability of the machine to automatically maintain its lateral equilibrium, I have equipped the machine with means for turning the shafts 10 slightly so as to change the relative position of the sprocket wheels 22 on said shafts and the sprocket wheels 21 10 on the wings with which they coöperate. The means herein shown for accomplishing this consists of driving members such, for example, as ropes or cables 23, which pass over pulleys 24 on the shafts 10 and over 20 a drum or drums 25 mounted on the body A of the machine and provided with gear teeth, worms or any other suitable driving means which coöperate with actuating device or devices 26 arranged adjacent the operator's seat 27 on the body A of the machine, as shown more clearly in Figs. 2 and 3. By actuating the device or devices 26 the operator can determine the point in the cycle of operations of the devices B at which 30 the wings reach their maximum working points or horizontal positions and their neutral points or vertical positions and thereby control the direction of lift of the combined propelling and sustaining means. 35 By this means said direction of lift may be maintained in an approximately vertical direction however far the machine may tilt over in a lateral direction and by this means the operator may also steer the machine in a 40 lateral direction.

Another desirable feature of such a construction is that the operator can accurately control the wings or planes of the machine when the devices B are disconnected from the motor or at rest as, for example, when 45 the machine is descending. That is to say, in case the motor stops, either accidentally or at the will of the operator, the operator can actuate the devices 26 so as to turn the 50 top wing or wings at the upper sides of the devices B into a horizontal position, and the two side wings pointing inwardly slightly or at such an angle that they offer resistance to the air in a vertical direction.

55 The means for guiding the machine consists of a vertical rudder 28 arranged at the rear end of the body A of the machine and two horizontal rudders 29 arranged on each side of the vertical rudder, as shown in Figs. 60 1 and 2, and pivotally connected to suitable supports on the body A of the machine, said rudders preferably being of similar construction to the wings or planes of the devices B. Ropes or cables 30 lead from a 65 horizontal cross-arm 31 on the vertical rudder

28 to a suitable controlling device D arranged adjacent the operator's seat 27, and suitable cables 32 lead from the upper and lower ends of vertical arms 33 on the horizontal rudders 29 to said controlling device D, the cables 30 and 32 being so arranged and the controlling device D being so constructed that the operator can swing the vertical rudder 28 laterally, and also move the horizontal rudders 29 upwardly and downwardly so as to guide the flight of the machine accurately.

The body or frame A of the machine is provided with wheels 34 which support the machine when it is not in the air, and said body A is so balanced, preferably by means of the motor C and the weight of the operator, that the front end of the body A is slightly heavier than the rear end so that the machine will tend to pitch forwardly and downwardly slightly when the combined propelling and sustaining devices B are set in operation. The resistance which the wings of the devices B offer to the air in a vertical direction when said devices are set in operation; or, in other words, the downward pressure which said wings exert on the air, causes the machine to rise from the ground and also move forwardly on account of the downward pitch of the front ends of said wings. The center of lift is some distance above the center of gravity of the machine so that the equilibrium of the machine is comparatively easy to maintain, and as the lift of the machine depends upon the power that is applied to the wings or planes of the devices B rather than upon the forward speed of the machine, the machine is able to lift itself directly from the ground without being propelled over the ground so as to give it momentum, as is necessary with the aeroplanes now in use. When the machine is in flight the operator adjusts the horizontal rudders 29 so as to cause the forward ends of the planes or wings w, x, y, and z to tip downwardly slightly and thus cause the air to exert pressure on the planes in such a manner that the machine is moved forwardly, the air striking against the under sides of the planes and moving rearwardly from the rear ends of the planes. In view of the fact that the longitudinal axes of the planes or wings w, x, y and z, extend parallel to the direction in which the machine moves through the air, said wings will cut through the air edgewise and thus offer very little resistance to the forward flight of the machine. As the speed of the machine increases a greater volume of air is brought into contact with the under sides of the wings, and consequently cuts down the rotary movement of the devices B which carry the wings. This is a very desirable feature of my machine because it overcomes the necessity of increasing the power that drives

the combined propelling and sustaining devices B when the speed of the machine increases. In other words, the rotative velocity of the wings or planes to maintain a certain lift becomes less and less as the forward speed of the machine increases. The wings or planes of the machine are so arranged that the thrust of same directly counteracts any tendency of the machine to descend, and by slightly tipping the forward end of the machine downwardly this thrust will directly counteract both the forward resistance of flight and the force of gravity combined. As some of the wings or planes of the machine always occupy a vertical position or a substantially vertical position said wings prevent the machine from skidding sidewise and thus enables the operator to accurately control the direction of the machine by manipulating the rudders at the rear end of same.

By dividing up the plane surface of the machine in the manner above described I am able to provide a machine of practicable size with a very large area of propeller plane surface and thus attain a high degree of efficiency per horse-power, and by applying the rotative power to the devices B in the manner above-described, namely, directly to the longitudinal axes of the planes or wings, said wings are not subjected to any excessive leverage or strains and I am thus enabled to mount said wings on a comparatively light frame-work or supporting structure which is strong enough to successfully withstand the strains to which it is subjected when the machine is in service. All rotative parts of the machine move at a relatively slow rate of speed so that there is very little waste of energy at the bearings of the rotative parts, and as the devices B and the body A of the machine consist of skeleton-shaped trussed frames, comparatively light members or small rods can be used to form said frames as the truss-wires equalize and distribute the strains uniformly to the various members used to form the frame.

Having thus described my invention, what I claim as new and desire to secure by Letters Patent is:

1. An aeroplane comprising a substantially box-shaped frame of skeleton-like construction in which the operator sits, braces that project upwardly and laterally from said frame, combined propelling and sustaining devices rotatably mounted in said braces and arranged on opposite sides of said frame, each of said devices consisting of a horizontally disposed axle provided with radially projecting supports in which wings or planes are rotatably mounted, driving wheels on the axles of said devices whose rims lie outside of the bearings of said planes, a

motor on the operator's frame, flexible driving members actuated by said motor and passing around the rims of said driving wheels, means for causing the rotative velocity of the combined propelling and sustaining device at one side of the machine to be accelerated automatically when the rotative velocity of the device on the other side of the machine is retarded by varying air currents, and tail-planes or rudders at the rear end of the machine under control of the operator for guiding the machine.

2. An aeroplane comprising the combination of a frame or body portion for carrying the operator and motor, rotatable propelling and sustaining devices arranged above and on opposite sides of said body portion and each comprising a plurality of pivotally mounted planes or blades whose longitudinal axes extend in the same general direction as that in which the machine travels through the air, means for causing said planes or blades to feather during their rotative movement around their respective central propeller shafts, said feathering means comprising sprocket wheels rigidly attached to the shaft of each blade and corresponding sprocket wheels rigidly attached to their respective central propeller shafts and the two co-operatively connected by a sprocket chain, means for controlling and adjusting said feathering means whereby the direction of lift of the propelling and sustaining means may be maintained in an approximately vertical direction, means for rotating said propelling and sustaining devices in opposite directions, and automatic means associated with the driving means adapted to maintain the center of lift at a point midway between the right and left propelling and sustaining devices.

3. An aeroplane comprising the combination with a main frame or body portion for carrying the motor, operator, controlling and steering devices, propelling and sustaining devices arranged above and on opposite sides of said body portion and rotatable on central shafts parallel to the longitudinal axis of the machine and each of said devices comprising a plurality of pivotally mounted planes or blades whose longitudinal axes extend parallel to said central shafts, means for rotating said devices in opposite directions and at such equal or varying rotative speeds that the center of lift will be maintained at a point midway between the two, means for causing said planes or blades to feather during their rotative movement around their respective central shafts, said feathering means comprising sprocket wheels rigidly attached to the shaft of each blade and corresponding sprocket wheels rigidly attached to their respective central propeller shafts and the two co-operatively

connected by a sprocket chain, means adapted to rotate and adjust said normally stationary central propeller shafts, said rotating and adjusting means comprising an actuating device situated in the body portion of the machine, having a rotative member, sprocket wheels or drums rigidly attached to the central shaft of each propeller and the two rotative members coöperatively con-

nected by flexible means, all substantially as 10 described and for the purpose set forth.

In testimony whereof I hereunto affix my signature in the presence of two witnesses, this twenty third day of June 1911.

JOHN E. McWORTER.
